UNITED STATES PATENT OFFICE.

AUGUST F. RICHTER, OF WATERTOWN, AND FRANK A. AUGSBURY, OF OGDENSBURG, NEW YORK, ASSIGNORS TO STEBBINS ENGINEERING AND MANUFACTURING COMPANY, OF WATERTOWN, NEW YORK, A CORPORATION OF NEW YORK.

METHOD AND APPARATUS FOR TREATING FIBER.

Application filed July 19, 1926. Serial No. 123,348.

This invention relates to an improved process and apparatus for treating wood chips or the like for making paper pulp, and more particularly to a novel process and apparatus for disintegrating fibers by acid treatment, and recovery of waste heat, gas and liquor.

The apparatus and method hereinafter described are exemplified as applied to the sulphite process, but they are also applicable to all chemical pulp processes in which gas is discharged from the digester during treatment.

In general, where the quick cook or direct steaming process of cooking is employed, the relief gases driven off from the liquor in the digesters during the cooking process, are passed through relief gas coolers and after being cooled, this gas is passed into the bottom of the acid storage tank or it is sometimes passed into the bottom of an absorption or recovery tower, the raw acid being sprayed into the top of the recovery tower and the gas, (in the case of the sulphite process, this is SO_2 gas) flowing upward under pressure meets the down coming acid and is absorbed. Heretofore, it has been necessary to cool the sulphur dioxide gas in order that it might be absorbed by the liquor. Due to this cooling, the acid, when pumped into the digester, requires an excess of steam to bring the temperature and pressure up in the digester.

It is also well known that quick cooks at high temperature have a destructive effect upon the cellulose in the wood, and low temperature cooks, (which necessarily take a longer time) do not have as destructive effect upon the cellulose. Further, when cooking is carried on at a comparatively low temperature, the yield of pure cellulose is higher. Our method and apparatus are applicable to both quick cook and slow cook systems.

In our process, no cooling of the gas from the digesters is required, as the gas is absorbed under pressure, thereby conserving the heat units with the direct result that there is a considerable saving of steam during the cooking process.

Briefly, one phase of the present invention consists in passing the hot high and low pressure relief gases from the digesters into an accumulator tank where the gases are ab-

sorbed by liquid acid, and in this absorption, the heat of the gases is also absorbed by the liquid under pressure, so that this heated acid may then be fed into a digester for treating the wood or other fibrous material arranged therein. In this way, heat is conserved and the liquid acid is in heated condition when it is applied to the fibrous material in the digester.

The invention is illustrated in the accompanying drawings, in which,

Fig. 1 is a diagrammatic view of one apparatus forming the subject matter of the present invention.

Fig. 2 is a similar view of a modification.

Fig. 3 is a vertical sectional view of a detail taken on line 3—3 of Fig. 1.

In general, the apparatus consists of one or more digesters, 1, 2, and 3, an acid accumulator 4, and one or more acid storage tanks 5 and 6. Although three digesters have been illustrated in Fig. 1, the application can be employed with any number of digesters, or with any number of acid storage tanks. In this connection, it may be stated that it is general practice to employ three acid tanks if three digesters are used, but only two acid storage tanks are used with the present invention, and these are combined with the acid accumulator 4.

The digesters employed are of the standard steel shell type now in common use, and in the sulphite process these digesters are lined with an acid resisting metal. Also the acid storage tanks 5 and 6 may be of steel or concrete with an acid resisting lining, or they may be made of wood. These pieces of apparatus are all in common use in many mills now operating. The acid accumulator is not now in use, but it may be of the same general construction as each of the digesters and must be provided with an acid proof lining.

We have shown the accumulator as arranged vertically, but it may be arranged horizontally and be as equally effective, provided that the same relative positions of the inlet and outlet pipes are maintained. This accumulator may be of any shape found desirable. The digesters and acid accumulator may or may not be covered with a heat insulator. As these pieces of apparatus are lined, the lining acts as an insulator, but additional insulation may be provided if necessary.

The raw acid in the case of the sulphite process may be made in any known way and pumped from the acid system to the storage tanks by way of the pipe 7.

5 The digesters are cooked in rotation, which is now common practice, and the wood chips or other fibrous material are introduced into the digesters from an overhead bin or chip conveyor (not shown) through sleeves 8
10 having covers 9. The liquid acid is forced into the bottom of the digester through pipe 10, either by an acid pump 11, or by applying steam pressure to the top of the accumulator 4, and driving the acid from the tank
15 4 through the pipe 12 and into the pipe 10. At this point, it will be noted that the pipe 10 is connected to the digesters by branch pipes 13, 14, and 15, each having a control valve 16, 17 and 18. The pipe 12 is also
20 provided with a control valve 19, and the pump 11 is connected to the bottom of the accumulator tank by a pipe 20 having a control valve 21.

If the acid from the accumulator 4 is to be forced into the digester by the pump 11, the valve 19 is closed and the valve 21 is opened, but if steam pressure is used instead of the pump, then the valve 21 is closed and the valve 19 is opened.

30 This method of forcing the acid into the digesters by pressure applied to the accumulator is new, and its advantages are that this steam pressure further heats up the acid.

35 thereby assuring a better penetration of the acid into the chips before the cooking process is started. One of the desired results is thereby accomplished, as it is always advantageous to have the acid as hot as possible in

order to secure quick penetration of the acid into the wood chips. The quicker this penetration is accomplished without carbonizing the chips, the better will be the pulp produced, besides saving time and investment. The pipe for introducing steam into the accumulator tank is shown at 22 and it is pro-

During the working process, the gas from

During the cooking process, the gas from the digesters is permitted to discharge into relief gas lines. In accordance with the present invention there are two relief lines provided; one a high pressure relief gas line 24, and the other a low pressure line 25. The pipe 24 is connected to each digester by two branches 26, each having a control valve.

55 27 therein. The low pressure pipe 25 is connected to each digester by two branches 28, each having a manually controlled valve 29 and an automatic check valve 30. Heretofore

fore, only one gas relief line has been used, but we find it advantageous under our method to employ two. During the first part of the cooking process and also during the last, part the pressure of the relief gas is relatively low and during these periods we admit the low pressure relief gas to the

65 we admit the low pressure relief gas to the

low pressure line 25, which is connected to the upper portion of the accumulator tank at the point 31. As the digesters are worked in rotation, there is almost a constant flow of low pressure gas into the accumulator 4 70 when three or more digesters are employed. If three or more digesters are used, the cold acid from the storage tank No. 5 is continuously forced by the pump 32 through pipe 33 and sprayed into the top of the accumulator 4. This cold liquid showering in the tank 4 condenses and absorbs the hot incoming relief gas from the pipe 25. If only one or two digesters are connected up to the acid accumulator, the pumping of acid is necessarily intermittent. 75 80

During the time that low pressure SO_2 gas is being relieved from some of the digesters into the top of the accumulator 4, SO_2 gas at high pressure is being relieved into the high pressure line 24, and carried into the bottom of the accumulator 4 from the other digesters. This high pressure relief gas passes into the tank 4 at the point 34 and bubbles up through the acid in the accumulator, and is thereby absorbed into the acid liquor, in this way building up the strength of the acid in the accumulator. A three way plug cock 35 is provided in the high pressure line 24 and is connected to the upper portion of the accumulator by a short pipe 36, so that gas from the high pressure line can be admitted into the top of the accumulator, when the pressure in the latter drops to a point below that caused by the static head of the acid liquor in the accumulator. This is particularly necessary when the last cook is being finished preparatory to a shut down, and also at certain periods when the digesters get out of step from their regular sequence of operation.

We will now assume that digesters Nos. 1 and 2 are already cooking, and No. 1 digester has been on for eight hours, and No. 2 for four hours. No. 3 digester has just been filled with chips and acid, and the cooking process just started. At this time, digesters 1 and 2 will both be relieving into the high pressure gas relief line 24. This gas passing into the bottom of the accumulator and bubbling up through the acid and being absorbed thereby. Due to this, the acid liquor in the accumulator 4 is heated up so that this heated liquor may be forced by the pump 11 or by steam introduced through the pipe 22, from the accumulator 4 into the lower end of the digester No. 3. As soon as the cook is started in digester No. 3, the valve 29 to the low pressure relief gas line is opened and the gas is driven out by the application of steam to this digester. In the event that the gas pressure on the top of the acid in the accumulator is higher than the pressure in the digester, the check valve 30 will close and prevent the flow of gas from

the accumulator back into the digester, but as soon as the pressure in No. 3 digester is higher than that in the accumulator, the gas will flow from No. 3 digester into the top of the accumulator where it will be absorbed by the acid which is being pumped and sprayed into the accumulator from the storage tank by way of pipe 33. After the cold acid is pumped from the storage tank 5 into the accumulator, it will condense and absorb the gas in the accumulator. Any gas that is not absorbed during this process will pass through the vent line 37, into the lower end of one or more of the digesters, or it may be passed through the pipe 38 into the lower portion of the storage tank 5 where it will be absorbed by the acid liquor in this tank. Suitable valves 39 and 40 are provided in these pipes to control the flow. A vent line 41 is also provided for the storage tanks 5 and 6, this vent line being led to the acid system (not shown), so that the gas which forms on the top of the acid storage tanks, will be absorbed in the acid making system, thus preventing the loss of gas.

As soon as No. 3 digester has been brought up to approximately 40 pounds pressure, the valves 29 of that digester are closed, and the valves 27 of the same digester are opened, so that the high pressure gas is released into the line 24. At this time, the digester No. 3 will have been cooked about four hours, and No. 1 digester will be ready to be dropped in pressure. As soon as the pressure in No. 1 digester drops, the valves 27 of that digester will be closed and the valves 29 of the same digester will be opened, to permit the low pressure gas to travel to the accumulator.

The above disclosure is based on a total cycle from fill to fill of approximately 16 hours for each digester, but it will be readily understood that in the event of shorter or longer periods of cooking, that the time stated above will be varied to meet conditions based upon the particular pulp desired.

Briefly summarizing the above described process, it may be seen that the high and low pressure gases issuing from the digesters, pass into the accumulator 4 and are absorbed under pressure, and in this operation they give off their heat to the acid liquor in the accumulator, so that this liquor is in pre-heated condition before it enters a digester which is about to be started. The steam for cooking is introduced to the digesters by the well known means now generally employed.

In the modification illustrated in Fig. 2, we have illustrated two accumulators, 50 and 51, hooked up with pressure or thermostatic control devices 52 and 53, (these are both standard equipment and can be purchased on the market) so that the relief gases from the digesters, and liquor from the acid stor-

age tanks 54 and 55 are automatically changed, from one accumulator to the other. That is, when one accumulator is up to a predetermined pressure, the gases and liquor are automatically switched over to the other 70 accumulator, leaving the first ready to discharge its contents into a digester whenever desired, this being automatically accomplished by opening the acid supply line leading into the digester. As the pressure and temperature in the first accumulator drops, due to emptying its contents and filling the digester, steam is automatically admitted to the top of this accumulator, maintaining the proper pressure therein to force the acid to 80 the digester which is being filled. During this period, the low pressure vent line at the top of the digester undergoing filling, is opened. In this modification, 24^a designates the high pressure relief gas line, which is 85 provided with a control valve 24^b. Just below the valve 24^b, the pipe is branched at 24^c, and these branches are connected to the upper portion of the accumulator tanks. The pipe extends downwardly and is connected by 90 valved branches 24^d to the lower portions of the accumulator tanks. The low pressure relief gas line is designated 25^a, and is connected by branches 25^b to the upper portion 95 of each accumulator tank.

The acid is supplied to the accumulator tanks by means of a pump 56 which forces the acid liquor through a pipe 57 having valved branches 58 connected to the tops of the accumulator tanks.

The acid is fed from the accumulator tanks to the digesters by means of a pipe 59 which is connected by valved branches 60 to the lower ends of the accumulator tanks.

Steam is supplied to the accumulator tanks by means of a pipe 61 having valved branches 62 connected to the tops of the accumulator tanks.

As soon as the digester has been filled from the first acid accumulator, the valve in 110 the acid supply line to the digester is closed and the steam at the top of the accumulator is shut off by closing the valve in the branch 62. This causes the temperature and pressure in this particular accumulator to drop, and as soon as it has dropped sufficiently, the automatic pressure or thermostatic control devices 52, 53, automatically changes the valves, so that this accumulator will again fill with acid from the storage tanks 54, 55, 115 while the gas from the digesters is being relieved into the same. It will therefore be noted that the two accumulators work automatically in conjunction with each other and automatically fill and absorb gas, and empty 120 themselves by manual control.

When these two accumulators are used, the check valves of the digesters are connected up electrically, so that when the low pressure check valve 30 closes, the operating valve 27 130

on the high pressure relief line is automatically opened. Such automatic regulation of valves is well known, and no specific means for accomplishing this need be illustrated.

5 Manual auxiliary control in this instance is also provided, so that digesters can be handled in this manner in case the automatic feature should for any reason fail to function. Occasionally, a check valve or an automatically controlled valve will stick, and under such circumstances, the digesters may be controlled by manual valves, that is the reason why we prefer to use two valved branches 26, and two valved branches 28 for 10 each digester.

Under our method of producing cellulose pulp, and handling digesters, we also prefer to provide a strainer at the bottom of each digester, so that when the cook is finished, 15 the liquor is drawn off at the bottom of the digester through this strainer. In Figs. 1 and 3 we have illustrated such strainers and have designated the same 70. The strainer holds back the cooked pulp and allows the 20 liquor to be drained out and sent to the sewer or else to the waste liquor fuel recovery system, or wherever it is required. During the time the liquor is drained out of the digester, hot water is being pumped into 25 the top through the line 71 which is provided with valved branches 72. This water draining down through the pulp, partially washes same, so that when the dumping valve, (not shown) is opened, the pulp is allowed to go 30 into the drain pits (not shown), or what are commonly called blow pits. The pulp is thus partially washed, and therefore does not contain much acid. As soon as the pulp has been partially washed in the digester, 35 this dumping valve or blow-off valve previously mentioned, is opened and the hot water entering the top of the digester will wash the contents of the digester out of the same and into the blow or draining pits. 40 Due to this operation the fibers do not explode as is the case when the contents of the digester are blown out under pressure, therefore the fibers are not injured and the pulp produced is of a better quality than that 45 produced when the liquor is not drained out, and the liquor and pulp are blown out into the blow pit by pressure applied to the interior of the digester. We also prefer to 50 arrange a hot water wash out line and that 55 is commonly called the "blow off elbow", so that this hot water comes in on a line parallel to the center line of the discharge pipe leading to the pits, thereby having a siphon effect in removing the contents of the digester. In our method, the contents of the 60 digester are handled much more gently than under the old practice, both as regards the cooking and the emptying, which produces a higher grade of pulp as above mentioned.

65 Our method of using the acid accumulator

is applicable to both quick and slow cooks, as also is the method of dumping or emptying the digesters, it only being necessary to so locate the blow or drainer pits, that it will not be necessary to elevate the contents of 70 the digester in order to get the same into the pits.

75 After the pulp has been discharged into the drainer pits, the washing is carried on in the same manner as is now general practice, and the cooking of the digester, that is the admittance of steam directly into the same for producing the required temperature and pressure, is accomplished in the same manner now generally employed in quick 80 cook systems.

85 The advantages of our method, however, are that the heat units in the relief gas and liquor, are conserved and the pulp produced is of a higher and purer quality.

90 Although we have not shown it, a side relief valve for removing part of the liquor during the cooking process is also provided. This relief discharges the liquor removed from the digester during the cooking process, back into the acid storage tanks, and this liquor is mixed with the raw liquor from the acid system, as is standard practice at this time.

95 From the foregoing, it is believed that the construction and operation of our apparatus, and the novel steps of our method, may be clearly understood, and it will be apparent to those skilled in the art that changes may be made in the details disclosed, without departing from the spirit of the invention as expressed in the claims.

100 What we claim and desire to secure by Letters Patent is:—

105 1. A method of treating fibrous material consisting in placing the same in closed chambers, digesting the material in one of said chambers with acid under heat and pressure, liberating low pressure gas from the last mentioned chamber for a period of 110 time, liberating high pressure gas from the last mentioned chamber for a subsequent period of time, contacting these gases with acid liquor under pressure to absorb the gas and heat the liquor, and introducing this heated liquor into the second chamber for digesting the material in that chamber.

115 2. A method of treating fibrous material consisting in feeding acid liquor into the upper portion of an accumulator chamber, placing the fibrous material in first and second digester chambers, digesting the material in the first chamber with acid under heat and pressure, releasing low pressure gas from the first digester chamber for a predetermined period of time and feeding the same into the upper portion of the accumulator chamber, subsequently releasing high pressure gas from the first digester chamber 120 and feeding the same into the lower portion 125 130

of the accumulator chamber, contacting said gases in the accumulator chamber with the acid liquor to absorb the gas and heat the liquor, and feeding this heated liquor into 5 the second digester chamber and contacting the same with the fibrous material therein for digestion purposes.

3. In a method of treating fibrous material, digesting the material with acid in a 10 closed chamber under heat and pressure, releasing gas from the chamber and contacting the same in heated condition with acid liquor to absorb the gas and heat the liquor, utilizing this liquor in heated condition for 15 digesting other fibrous material, and passing vent gas from the sphere of absorption into a second absorption chamber.

4. A method of treating fibrous material consisting in placing the material in first 20 and second digester chambers, digesting the material in one of said chambers with acid under heat and pressure, passing gas from the first chamber to an accumulator chamber, contacting the gas in the accumulator 25 chamber with acid liquor to absorb the gas and heat the liquor, and introducing steam into the accumulator chamber for heating the gas enriched liquor and for forcing the same in this heated condition into contact 30 with the material in the second chamber.

5. In an apparatus for treating fibrous material, a digester and an accumulator, a high pressure relief gas line connecting the digester to the accumulator, a low pressure 35 relief gas line connecting the digester to the accumulator, valves arranged in said lines, means for feeding acid liquor into the accumulator for absorbing the gas by the liquor, and heating the liquor by the gas, 40 and means for feeding the gas enriched heated liquor from the accumulator into the digester.

6. An apparatus for treating fibrous material comprising a digester and an accumulator, a high pressure gas line connecting the upper portion of the digester to spaced 45 points on the accumulator, one of said spaced points being arranged above the other, a valve for controlling the feed of the gas into the accumulator at one point or the other, means for feeding acid liquor into the accumulator for absorbing the gas and heating the liquor, and means for feeding this gas enriched heated liquor to the 55 digester.

7. An apparatus for treating fibrous material comprising a digester and an accumulator, means for feeding acid liquor into said accumulator, means for feeding relief 60 gas for the digester into the accumulator for contacting the gas with the liquor, a conduit connecting the accumulator to the lower portion of the digester, and means for feeding aqueous steam from an outside source 65 into the upper portion of the accumulator

for forcing the liquor through the conduit into the digester.

8. An apparatus for treating fibrous material comprising a digester, an accumulator, an acid storage tank, means for forcing and feeding acid liquor from the storage tank to the accumulator tank, a conduit for feeding acid liquor from the accumulator to the digester, a high pressure relief gas line connecting the upper portion of the digester to the lower portion of the accumulator, a low pressure relief gas line connecting the upper portion of the digester to the upper portion of the accumulator, and means for forcing acid from the accumulator to said 70 digester. 75

9. An apparatus as claimed in claim 8 including a vent gas pipe for leading gas from the accumulator to the storage tank.

10. An apparatus as claimed in claim 8, 80 including a by-pass pipe for connecting the high pressure relief gas line to the upper portion of the accumulator, and a valve for controlling the passage of high pressure relief gas to either the upper or lower portion 90 of the accumulator.

11. A method of treating fibrous material, consisting in placing the material in a chamber, placing acid liquor in a tank, introducing aqueous steam under pressure 95 from an outside source into said tank for preheating said acid liquor, and utilizing the pressure of the steam for forcing the preheated acid liquor from the tank into said chamber and into contact with the material in the chamber. 100

12. In an apparatus for treating fibrous material, a digester having a pulp outlet at its lower end, a screen in said outlet, means for introducing acid liquor into said outlet beneath the screen, and means for introducing hot liquid into the upper end of the digester for washing acid out of the material in the digester and through said screen. 105

13. A method of treating fibrous material, 110 consisting in placing a raw material in first and second digester chambers, digesting the material in the first chamber with acid under heat and pressure, releasing low pressure gas from the first chamber for a predetermined period of time, subsequently releasing high pressure gas from the first chamber for a predetermined period of time, contacting said gases with acid liquor under pressure 115 to absorb the gas and heat the liquor, and contacting the heated liquor with the fibrous material in the second digester chamber for digesting purposes. 120

14. A method of treating fibrous material, 125 consisting in feeding acid liquor into the upper portion of an accumulator chamber, placing the fibrous material in a digester chamber, digesting the material in the chamber with acid under heat and pressure, releasing low pressure gas from the digester 130

- chamber for a predetermined period of time and feeding the same into the upper portion of the accumulator chamber, releasing at another period of time, high pressure gas from the digester chamber and feeding the same into the lower portion of the accumulator chamber, contacting said gases in the accumulator chamber with acid liquor under pressure to absorb the gas and heat the liquor, and contacting this heated liquor with fibrous material for digestion purposes.
15. In a method of treating fibrous material, digesting the material with a chemical solvent in a number of closed chambers under heat and pressure, releasing gas from the chambers and contacting the same in heated condition with pre-conditioned chemical solvent in an accumulator chamber under superatmospheric pressure to absorb the gas and heat the solvent, releasing gas from one of said chambers and contacting the same with fresh chemical solvent of a supply chamber arranged at a lower elevation than the top of the accumulator chamber, pumping pre-conditioned chemical solvent from the supply chamber into the accumulator chamber, and feeding the chemical solvent from the accumulator chamber, into one of said closed chambers.
20. 16. In a fiber treating method, digesting the fiber in a plurality of closed chambers under superatmospheric pressure with heated acid liquor, releasing acid gas from said closed chambers and passing the same into a closed accumulator chamber, contacting said gas in the accumulator chamber with pre-conditioned acid liquor, releasing acid gas from one of said chambers and contacting the same with fresh acid liquor of a storage tank arranged at a lower elevation than the top of the accumulator chamber to pre-condition said fresh acid liquor, feeding the fresh acid liquor thus pre-conditioned from the storage tank into the accumulator chamber, and passing the acid liquor from the accumulator chamber into one of said closed chambers.
25. 17. In a fiber treating method, digesting the fiber in a closed chamber with a heated chemical solvent, releasing gas from said closed chamber and passing the same in its heated condition into an accumulator chamber, feeding fresh chemical solvent from a supply tank arranged at a lower elevation than the top of the accumulator chamber, 55 into the accumulator chamber, and contacting the same in the latter chamber with the heated gas released from the closed chamber, to absorb a portion of the gas and to heat said chemical solvent, releasing gas 60 from one of said chambers and passing the same into the chemical solvent of the supply tank for pre-conditioning the solvent in the latter tank, and passing the chemical solvent from the accumulator chamber in its 65 pre-heated condition into said closed chamber.
18. In a method of treating fibrous material, digesting the material with a chemical solvent in a closed chamber, releasing high pressure gas from said closed chamber for a period of time, and passing the same in heated condition into a second chamber, contacting said gas in the latter chamber with chemical solvent, releasing low pressure gas from said first closed chamber for another period of time, and contacting said low pressure gas in heated condition with fresh chemical solvent, and feeding the solvent after it has been heated by said contact into a closed chamber for digesting fibrous material.
19. A method of treating fibrous material, consisting in placing the same in closed chambers, digesting the material in one of said chambers with acid under heat and pressure, liberating high pressure gas from the last mentioned chamber for a period of time, liberating low pressure gas from the last-mentioned chamber for a subsequent period of time, contacting these gases with acid liquor under pressure to absorb the gas and heat the liquor, introducing this heated liquor into the second chamber for digesting the material in that chamber, discharging the acid from the first chamber while retaining the material therein, washing the material with liquid while it is contained in the first chamber, and utilizing a liquid to wash the material out of the first chamber.
